UNITED STATES PATENT OFFICE.

JAMES D. PARKER, OF KANSAS CITY, KANSAS.

VENTILATING FAN.

Application filed August 5, 1926. Serial No. 127,433.

The invention relates to improvements in ventilating and air circulating fans, and more particularly to certain improvements in the fan for which Letters Patent of the United States Number 1,587,031 was issued to me June 1, 1926.

The inner end of the blades of the fan of my former invention are secured to wings that extend diagonally the length of the hub, and the only practical method now known of forming the hub is to cast it with a dry sand core between each adjacent pair of wings. It has been found in practice that the moulding and baking of the number of cores required daily is objectionable from a productive standpoint, provided the cores can be eliminated and the same high efficiency of the fan maintained.

The present invention has provided a fan with a hub so shaped that it is easily cast in green sand moulds and the wings formed without the employment of cores, together with certain other improvements.

With these and other objects in view the invention consists in the features of construction, combinations and arrangements of parts hereinafter set forth and more particularly pointed out in the appended claims, the accompanying drawings illustrating a fan with the improved form of hub, and which attains the same high efficiency of the fan of my former invention.

In the drawings:—

Fig. 1 is a view in elevation of the intake and suction side of a fan embodying the features of my present invention.

Fig. 2 is an enlarged fragmentary broken view of the fan with all but one of the blades removed.

40 Figs. 3, 4, 5 and 6 are further enlarged.

Fig. 3 is an end view of the hub of the improved fan.

Fig. 4 is a longitudinal view of the hub broken open on line 4—4 of Fig. 3.

45 Fig. 5 is a longitudinal view of the hub broken open on line 5—5 of Fig. 3, with a fragment of each of two oppositely positioned blades attached and the intervening wings removed with the broken part of the hub.

50 Fig. 6 is a longitudinal view of the hub at a rotary angle of approximately 90 degrees

from that of Fig. 5, with a fragment of a blade attached, and one of the wings broken away to save room in illustrating.

55 Figs. 7, 8 and 9 are still further enlarged.

Fig. 7 is a sectional view taken on line 7—7 of Fig. 2.

Fig. 8 is a sectional view taken on line 8—8 of Fig. 2.

Fig. 9 is a sectional view taken on line 9—9 of Fig. 2.

60 Figs. 10 to 17 inclusive are slightly modified forms and are of the same scale as Figs. 3, 4, 5 and 6.

65 Fig. 10 is approximately the same view as Fig. 4 and illustrates the same hub as that shown in Figs. 3, 4, 5 and 6 excepting the hub is straight instead of slightly tapering.

70 Fig. 11 is the same as Fig. 10, but with two oppositely positioned blades attached, the blades being shown in fragmentary view.

75 Figs. 12, 13, 14 and 15 show the same hub as that of Figs. 10 and 11, but with the spiral connections of the wings extended to the center of the hub longitudinally, Fig. 12 being a side view, Fig. 13 a broken side view with two oppositely positioned blades attached, Fig. 14 an end view with two blades attached, and Fig. 15 the opposite end with two blades attached, the blades being shown in fragmentary view.

80 Figs. 16 and 17 are the same as the hub illustrated in Figs. 3 to 6 inclusive, excepting the hub is separated and formed in two parts so that the same hub may be employed for different dimensioned fans.

85 The shaft 1, ring 2, spoke center 3, spokes 4 and the attachment of the blades 5 to the main stays 6, back stays 7 and ring 2 by wrapping the edge of the blade around the stays and ring as illustrated in Figs. 2, 7, 8 and 9 are not new and are shown merely to show the relations of the improvements thereto.

90 The hub body 8 is of approximately cylindrical shape, is bored to receive the shaft 1 and secured thereto, the setscrew 9 illustrating the usual method of securing the shaft in the hub. The hub body 8 is provided with the wings 10 at the air receiving end 11 thereof and with the wings 12 at the air discharge end 13 thereof, this with reference to the direction of the travel of the air

blast over the hub when the fan is in operation. The fan is rotated in the direction indicated by the arrows shown in Figs. 1 and 3.

- 5 The blades 5 lay against the blade bearing faces 14 and 15 of the wings 10 and 12 respectively and are bolted thereto by the respective bolts 16 and 17 which also pass through the main stays 6 and back stays 7 respectively, the blades being secured to the stays by the respective rivets 18 and 19 and by forming the edges of the blade around the stays as shown in Figs. 7 and 8.

- 15 The blades 5 are secured to the ring 2 by the rivets 20 and by folding the edge of the blade around the edge of the ring as shown in Fig. 9.

- The wings 10 and 12 are integral with the hub body 8 as shown and are so positioned 20 that the blade bearing faces 14 and 15 lie in an approximate common plane radially disposed from the axis of the hub near the center of the length thereof and converge considerably laterally in opposite directions 25 from the axis at the two ends of the hub, so that with reference to the direction of rotation of the fan and hub, each blade bearing face 14 is considerably in advance of the companion blade bearing face 15.

- 30 The wings 10 and 12 are joined to the hub body 8 by the spirally disposed connecting ribs 21 and 22 respectively and the hub body is smaller in diameter near the center of its length 23 than at the ends 11 and 35 13, so that the end 24 of the blade 5 is straight as shown in Fig. 5 and the blade bears against the hub body between the wings 10 and 12 so that no air current can pass between the blade and the hub.

- 40 The wings 12 are beveled along the inner edge 25 thereof so that no obstruction will be encountered by the flow of air when the fan is in operation.

- Figs. 10 and 11 illustrate a slightly modified form wherein the hub body 8^a is formed straight and the blades 5^a are curved at the ends 24^a thereof so as to abut the hub body and prevent air currents around the hub, this form being otherwise the same as that shown in Figs. 3 to 6 inclusive.

- 45 In Figs. 12, 13, 14 and 15 a further modified form is illustrated wherein the spiral ribs 21^b and 22^b are extended to near the center longitudinally of the hub body 8^b and 55 form a backing for the blades 5^b so that the blades are formed in a straight line across the ends 24^b and no air can pass between the hub and the blades.

- In Figs. 16 and 17 a still further modified 60 form is illustrated wherein the hub body 8^c is separated and formed in two pieces. A two piece hub of this form is more easily cast and may be employed for more than one size of fan.

- 65 Fig. 16 shows the two parts of the hub 8^c

abutting for a small fan and Fig. 17 illustrates the hub further separated for a larger fan, the blades 5^c being formed to abut the hub and the shaft 1^c. In this construction the two parts of the hub 8^c must be 70 held rigidly in the required relative rotary position to maintain the proper pitch of the blades 5^c and the setscrews 9^c are shown for this purpose, the screws being sunk into the shaft 1^c as indicated by dotted lines at 26. 75

The wings 10 and 12, 10^a and 12^a, 10^b and 12^b and 10^c and 12^c are all uniform and all are secured to the respective hub bodies in the same manner.

In the preferred form illustrated in Figs. 80 1 to 9 inclusive as well as in all the modified forms, the blades are in close proximity to the hub and prevent air currents around the hub and shaft and under the blades, so there is no backlash or reverse currents of air. 85

It will be noted that the blades are closer to the axis of the hub at the longitudinal center thereof than at either end of the hub, and there being no wings at this point allows more air to pass through the fan, so that 90 greater efficiency is attained in a given diameter of fan. The fan also runs more smoothly and noiseless and can be run at greater speed, owing to the reduced weight of the hub, there being less weight to vibrate. 95

All claims appended hereto which may conflict with the claims of my former Patent No. 1,587,081, issued to me June 1, 1926, for ventilating fan, shall be subject thereto.

Having described my invention, what I 100 claim as new and desire to secure by Letters Patent, is:—

1. A fan comprising a hub of approximately cylindrical shape, a series of wings spaced apart circumferentially around each end of said hub, each of said wings on one end of said hub a companion of a wing on the opposite end of said hub, each companion pair of said wings disposed in a common spiral along the cylindrical periphery of said hub and then changing to a flat rectangular shape so that the flat rectangular portion of each companion pair of said wings lie in a common plane disposed radially from and crossing the axis of said hub near the center of the length thereof at an acute angle to the axis of said hub, and a flat blade bearing against and secured to the flat rectangular portion of each companion pair of said wings and projecting from said hub in the same general direction as the flat portion of said wings. 115

2. A fan comprising a hub of approximately cylindrical shape, a series of wings spaced apart circumferentially around each end of said hub, each of said wings on one end of said hub a companion of a wing on the opposite end of said hub, each companion pair of said wings disposed in a common spiral along the cylindrical periphery 120 of said hub and then changing to a flat rectangular shape so that the flat rectangular portion of each companion pair of said wings lie in a common plane disposed radially from and crossing the axis of said hub near the center of the length thereof at an acute angle to the axis of said hub, and a flat blade bearing against and secured to the flat rectangular portion of each companion pair of said wings and projecting from said hub in the same general direction as the flat portion of said wings. 125

- 65 Fig. 16 shows the two parts of the hub 8^c

of said hub and then changing to a flat rectangular shape so that the flat rectangular portion of each companion pair of said wings lie in a common plane disposed radially from and crossing the axis of said hub near the center of the length thereof at an acute angle to the axis of said hub, a blade

attached to the flat rectangular portion of each companion pair of said wings, and said blade in close proximity to said hub from 10 end to end thereof so that no air current can pass between said hub and said blades.

JAMES D. PARKER.
